US00D917500S

(12) **United States Design Patent** (10) **Patent No.:** **US D917,500 S**
(45) **Date of Patent:** **** Apr. 27, 2021**

(54) **DISPLAY SCREEN OR PORTION THEREOF
WITH GRAPHICAL USER INTERFACE**

(71) Applicant: **Ethicon LLC**, Guaynabo, PR (US)

(72) Inventors: **Tony C. Siebel**, Cincinnati, OH (US);
John V. Hunt, Cincinnati, OH (US);
Brett E. Swensgard, West Chester, OH (US);
Douglas E. Withers, Cincinnati, OH (US);
Richard L. Leimbach, Cincinnati, OH (US);
Raymond E. Parfett, Loveland, OH (US);
Shane R. Adams, Lebanon, OH (US);
Brian D. Schings, Cincinnati, OH (US);
Kevin D. Sackett, Independence, KY (US)

(73) Assignee: **Ethicon LLC**, Guaynabo, PR (US)

(**) Term: **15 Years**

(21) Appl. No.: **29/619,600**

(22) Filed: **Sep. 29, 2017**

(51) LOC (13) Cl. **14-04**

(52) U.S. Cl.

USPC **D14/485**

(58) **Field of Classification Search**

USPC **D14/485-495**

CPC **A61B 17/068; A61B 2017/00398; A61B**

18/1455

Primary Examiner — Richelle G Shelton

(57) **CLAIM**

The ornamental design for a display screen or portion thereof with graphical user interface, as shown and described.

DESCRIPTION

FIG. 1 is a front view of a display screen or portion thereof with graphical user interface; FIG. 2 is a second embodiment thereof; FIG. 3 is a third embodiment thereof; and, FIG. 4 is a fourth embodiment thereof. The broken lines show a display screen or portion thereof and form no part of the claimed design.

1 Claim, 4 Drawing Sheets
